UNITED STATES PATENT OFFICE.

HENRY HIGGIN, OF NEWPORT, KENTUCKY, ASSIGNOR TO THE HIGGIN MANUFACTURING COMPANY, OF NEWPORT, KENTUCKY, A CORPORATION OF WEST VIRGINIA.

ELEVATOR SAFETY-LOCK.

No. 895,562.

Specification of Letters Patent.

Patented Aug. 11, 1908.

Application filed June 30, 1906. Serial No. 324,272.

To all whom it may concern:

Be it known that I, HENRY HIGGIN, a citizen of the United States, and a resident of the city of Newport, in the county of Campbell and State of Kentucky, have invented 5 certain new and useful Improvements in Elevator Safety-Locks, of which the following is a specification.

The several features of my invention and 10 the various advantages resulting from their use conjointly or otherwise will be apparent from the following description and claims.

In the accompanying drawings making a 15 part of this application, and in which similar letters of reference indicate corresponding parts, Figure 1 is a view in perspective of a mechanism embodying my invention. Fig. 2 is a top view of the clamping mechanism. Fig. 3 is a view of the bottom or under side 20 of the clamping device. Fig. 4 is a detail view of the left hand end portion of the device shown in Fig. 3. Fig. 5 is a view of the bushings of the clamping device. Fig. 6 is a vertical transverse section taken in the 25 plane of the dotted line 6, 6, of Fig. 3. Fig. 7 is a view in perspective of that end portion of the clamping device which is at the right in Fig. 2. In this Fig. 7, the rotatable screw sleeve or nut and its lever are shown un- 30 coupled from the non-rotatable screw.

I will now proceed to describe my invention in detail.

A indicates the controller rope of the elevator. There are certain occasions on which 35 it is desirable to hold this rope stationary, and so that it cannot be accidentally shifted up or down.

The object of my invention is to provide 40 the clamping means for holding this rope stationary and so that it cannot be shifted unless this special means is actuated by human agency. The clamping device is preferably located at a height above the elevator car floor sufficient to enable it to be 45 conveniently reached by the hand of the operator.

The mode of support may be varied to suit 50 the wishes of the user and the structures adjacent. Ordinarily, an upright post B, pref- erably of iron, having an outspread foot- piece B², secured by bolts or screws B³, passing through the foot piece and into the floor will be one of the most convenient supports.

The upper end of the support is provided 55 with an expanded top, or table B⁴. On this the clamping mechanism is supported.

The clamping mechanism consists as follows: There is a body piece C provided with suitable means for securing it in place on the support to which it is connected or attached. 60 The preferred means for thus securing it in place, are the ears or flanges C², C², respectively extending out from the respective sides of this body piece C near the bottom of the latter, and when the support is of the 65 kind shown in the drawing, these flanges C², C², are secured to the top B⁴ by screws or by the bolts B⁵. In this body piece C are two parallel grooves respectively marked C³, C³. Between these grooves C³, C³, is a 70 tongue or long straight rib C⁴. This rib extends out toward the rope A beyond the adjacent end of the body C. Its outer end is adapted to receive a part of the bushing with which this end portion of the clamping 75 mechanism is fitted.

In each groove C³ is located a rod or piece D, adapted to slide back and forth in this groove. Those ends of these rods D which are nearest the rope, extend out beyond the 80 tongue or rib C⁴ and are then duly joined, forming an end D². This end piece D² may be originally separated from the rods D, D, and be connected to them, or may, as shown, and as I prefer to constitute it, be in one 85 piece with these rods D, D. As I adapt this end for a bushing, its inner side is formed to receive the same.

The kind of bushing which I prefer to employ is that shown in Fig. 5. It consists of 90 two semi-cylinders E, E, each provided at each end with a flange E², E². These flanges prevent their semi-cylinders from leaving the opening between the end of the tongue C⁴ and the end D² of the rods D, D. The interior 95 of each bushing is suitably corrugated, or ribbed, to enable the bushings to have a firmer grip on the rope. The ribs E³ in the present instance run diagonally to the length of the bushing.

The rear end portions of the rods D, D, are provided with a screw thread H. This thread is interrupted at two opposite points by the tongue C⁴, but otherwise it is spirally continuous, and as shown.

The rotatable sleeve K has a screw thread

100

105

K². This screw thread engages the thread H on the rods D, D. This screw sleeve is prevented from leaving its place on the screw H by means of the tongue C⁴, which 5 extends rearward and connects with a rear holding disk or abutment C⁵, being secured thereto by a screw or pin C⁶, which latter passes through the opening C⁷ of the disk C⁵ and the opening C⁸ of the tongue or piece C⁴.

10 The rotatable screw sleeve K is operated by a lever K³. Rotation of this sleeve K in one direction operates to advance the rods D, D, thus moving them and their union end D² with its bushing E away from the tongue 15 C⁴ and its bushing E. The rope A is then perfectly free to travel up and down through the bushings, that is, through the clamp without interruption. Rotation of this sleeve K in the other direction operates to 20 retract the rods D, D, and draw their union end with bushing close to the bushing of the tongue C⁴. This operation binds the rope fast in this clamp, and prevents the rope A from moving up or down,—that is, the rope 25 is held stationary until the clamp is loosened.

I provide suitable means for keeping the rotatory movement of the rotatable screw sleeve K within fixed and useful limits. A preferred construction therefor is as follows: 30 I provide a pin K⁴ on the end of the rotatable sleeve, and a recess K⁵ in the rear holding disk or abutment C⁵ of the clamp. The pin K⁴ moves in this recess K⁵, and its movement is limited by the ends K⁶, K⁶, of this 35 recess K⁵. Of course, the pin K⁴ might be on the body C, and the recess in the rotatable sleeve K, or vice versa, but the illustrated device is preferable.

Bushing is not absolutely necessary for the 40 operation of my clamp, but its presence is obviously very much to be desired.

My invention is simple, economical and highly efficient.

One advantage resulting from my invention 45 is that in the construction and use of the rope, the ordinary buttons usually present may well be omitted.

The place on the rope where the rope is to be grasped by the safety lock, when the elevator is to be stopped, may be indicated by 50 painting the rope there, or by putting there a piece of bright metal which latter may be constantly in view.

My invention saves the expense of button 55 stops, and makes the stop a positive one.

It is to be noted that the device can be used for purposes other than for starting and stopping elevators.

What I claim as new, and of my invention 60 and desire to secure by Letters Patent, is:—

1. In a clamp, the body C, provided with grooves C³, C³, a stationary tongue C⁴, rods D, D, sliding in said grooves, and having a 65 clamping end for operating in conjunction with the tongue, and means for advancing

and retracting the rods D, D, relatively to the tongue C⁴, substantially as and for the purposes specified.

2. In a clamp, the body C provided with grooves C³, C³, a stationary tongue C⁴, rods 70 D, D, sliding in said grooves, and having an end D², the rods D, D, provided with a screw thread, a rotatable screw sleeve engaging the screw thread of the rods D, D, and means for holding this screw sleeve to place, substantially as and for the purposes specified. 75

3. In a clamp, the body C provided with grooves C³, C³, a stationary tongue C⁴, rods 80 D, D, sliding in said grooves, and having an end D², the rods D, D, provided with a screw thread, a rotatable screw sleeve engaging the screw thread of the rods D, D, and a detent at rear of this rotatable screw sleeve secured to the tongue, substantially as and for the purposes specified. 85

4. In a clamp, the body C provided with grooves C³, C³, a stationary tongue between these grooves and united to the body C, rods sliding in the grooves and having a clamping end for operating against the tongue, said 90 rods D, D, provided with the screw thread H, a rotatable sleeve whose screw thread engages screw thread H of the rods D, D, means for rotating the sleeve, the part C⁵ for holding the sleeve in place on the screw thread H, 95 this part C⁵ and another member as the sleeve, being respectively provided with stop shoulders, and a stop pin, for limiting the movement of the sleeve, substantially as and for the purposes specified. 100

5. In a clamp, the body C provided with grooves C³, C³, a stationary tongue between these grooves and united to the body C, rods sliding in the grooves and having a clamping end for operating against the tongue, said 105 rods D, D, provided with the screw thread H, a rotatable sleeve whose screw thread engages screw thread H of the rods D, D, means for rotating the sleeve, and means for limiting the distance through which the sleeve rotates, substantially as and for the purposes specified. 110

6. In a clamp, the body C, provided with grooves C³, C³, a stationary tongue C⁴, rods D, D, sliding in said grooves and having a 115 clamping end portion for operating with said tongue, this clamping end on the side next the said tongue being of a semi-cylindrical concave shape, and the adjacent end portion of said tongue being also of a semi-cylindrical concave shape, and means for advancing and retracting the rods D, D, relatively to this tongue C⁴, substantially as and for the purposes specified. 120

7. In a clamp, the body C provided with grooves C³, C³, a stationary tongue C⁴, rods D, D, sliding in said grooves and having a clamping end portion for operating with the said tongue; this clamping end portion on the side next the tongue being of a semi- 125 130

cylindrical concave shape, and the adjacent portion of said tongue being also of a semi-cylindrical concave shape, and the two part bushing, each part thereof consisting of a shell of a semi-cylindrical shape inside and outside, one portion occupying the concavity of the tongue, and the other portion occupying the concavity of the clamping end portion of the rods, and means for advancing and retracting the rods D, D, relatively to this tongue C⁴, substantially as and for the purposes herein specified.

8. In a clamp, the body C provided with grooves C³, C³, a stationary tongue C⁴, rods D, D, sliding in said grooves and having a clamping end portion for operating with the tongue, this clamping end portion on the side next the tongue being of a semi-cylindrical concave shape, and the adjacent portion of the said tongue being of a semi-cylindrical concave shape; and the two part bushing, each part thereof consisting of a shell of a semi-cylindrical shape inside and outside, one part occupying the concavity of the tongue, and the other portion occupying the concavity of the clamping end portion of the rods, the inside part of each bushing having a spirally corrugated or ribbed surface, and means for advancing and retracting the rods D, D, relatively to this tongue C⁴, substantially as and for the purposes herein specified.

9. In a clamp, the body C provided with grooves C³, C³, a stationary tongue C⁴, rods D, D, sliding in said grooves and having a clamping end portion for operating with the tongue, this clamping end portion on the side next the tongue being of a semi-cylindrical concave shape, and the adjacent portion of the said tongue being of a semi-cylindrical concave shape; and the two part end flanged bushing, each part thereof consisting of a shell of a semicylindrical shape inside and outside, one part occupying the concavity of the tongue and the other part occupying the concavity of the clamping

portion of the rods, the flanges of each one of the two complementary parts of the bushing respectively overlapping the upper and lower surfaces of the said clamping end portion and of the said tongue, and means for advancing and retracting the rods D, D, relatively to this tongue C⁴, substantially as and for the purposes specified.

10. In a clamp, the body C provided with grooves C³, C³, a stationary tongue between these grooves and united to the body C and having a clamping end of a semi-cylindrical concave shape, rods sliding in the grooves and having a clamping end for operating against the tongue and which end is of a semicylindrical concave shape on the side next the adjacent end of the tongue, the rods D, D, provided with the screw thread H, a rotatable sleeve provided with a screw-thread engaging screwthread H of the rods D, D, means for rotating the sleeve, the part C⁵ for holding the sleeve in place on the screw thread, this part C⁵ and another member as the sleeve being respectively provided with stop shoulders and a stop-pin for limiting the movement of the sleeve, substantially as and for the purposes specified.

11. In a clamp, the body C provided with grooves, C³, C³, a stationary tongue between these grooves and united to the body C and having a clamping end for operating against the opposing portion of the clamp, the rods D, D, provided with the screw thread H, a rotatable sleeve whose screw-thread engages the screw thread H of the rods D, D, handle K³ connected to the sleeve, the part C⁵ for holding the sleeve in place on the screw thread H, this part C⁵ and another member as the sleeve, being respectively provided with stop shoulders and a stop pin for limiting the movement of the sleeve, substantially as and for the purposes set forth.

HENRY HIGGIN.
